CARD DISPLAY HOLDER

Robert Fisher, 24 Burroughs Road, Balwyn,
Victoria, Australia

Filed Feb. 18, 1965, Ser. No. 83,862

Term of patent 14 years

(Cl. D1—3)

FIG. 1 is a perspective view of a card display holder showing my new design, a portion being broken away for convenience of illustration;

FIG. 2 is a rear elevational view of FIG. 1;

FIG. 3 is a sectional view taken along the line III-III of FIG. 2;

FIG. 4 is a perspective view of the holder on a reduced scale, the broken line representation of price tags being for purposes of illustration only.

I claim:

The ornamental design for a card display holder, substantially as shown and described.
